(57) **CLAIM**

The ornamental design for a overhead fluorescent light housing, as shown and described.

DESCRIPTION

FIG. 1 is a perspective view of the overhead fluorescent light housing according to the present invention;

FIG. 2 is a front elevational view thereof; the back elevational view being identical thereof;

FIG. 3 is a top plan view thereof; and,

FIG. 4 is a view of one end thereof; the other end being identical thereof.

The broken lines shown in the drawings represent portions of the overhead fluorescent light housing that form no part of the claimed design.
